PLATE REGISTERING MACHINE

Henry A. Wise Wood, New York, N. Y.; Elizabeth Ogden Wood, executrix of Henry A. Wise Wood, deceased, assignor to Wood Newspaper Machinery Corporation, Plainfield, N. J., a corporation of Virginia

Application July 29, 1937, Serial No. 156,252

16 Claims.

(Cl. 29—21)

This invention relates to the registering of successive castings or other articles so that they may be put through a machine to work on them subsequently in exactly registered position for the purpose of making the final products exactly alike or exactly in registration. Its particular value lies in the stereotyping art and in the preparation of semi-cylindrical printing plates which are used on rotary printing presses, especially where color printing is involved. It involves the pre-registration of plates before placing them on the printing press so that all of them will be in the same relative position when receiving ink.

The objects of this invention are to provide means whereby considerable time and effort are saved because a plate may be registered, or any out-of-registration plate discovered, before the plate is actually put on the printing cylinder; to provide a combination of means for correctly registering each plate by a set of stationary locating devices, such as mirrors, so that the plate can be adjusted by the use of these mirrors to fit preset register marks and then the plate marked or notched by the present machine so the plate can be accurately aligned for machining the plate; to provide means whereby, when a series of plates are registered on this machine and then finished on another machine and placed on a set of printing cylinders which are themselves uniform, registration will be obtained necessarily from a plate on one printing couple to a plate on the next successive printing couple without complicated manipulations; to provide means whereby, if a plate is imperfect due to some process in stereotyping, or the like, this fact will be discovered and that plate discarded or remade before it is even sent to the press room; to provide a plate holding saddle having end plate clamps with improved means for operating the plate clamps simultaneously by hand; to provide this saddle and a plate lifting means in a complete assembly constituting an individual unit; to provide means for supporting the saddle so that it is pivoted at its center and can swing without throwing the plate lifting means out of effective operation; to provide hand mechanism for turning the saddle through an angle; to provide hand operated means for moving the plate clamps and turning the saddle to cause previously registered marks on the plate to coincide with register marks attached to the stationary frame of the machine; to provide broaches to make register notches on the plate and simple but accurate means for operating them; to provide means for automatically shut-

ting off the motor which operates the broaches, and to provide a complete machine which is compact and easily assembled for accomplishing all of the above mentioned results.

Other objects and advantages of the invention will appear hereinafter.

Reference is to be had to the accompanying drawings, in which:

Fig. 1 is a front elevation of a plate registering machine constructed in accordance with this invention;

Fig. 2 is a sectional view of the lower part of the machine showing the means for raising and lowering the saddle;

Fig. 3 is an end view thereof, as indicated by the arrow 3 in Fig. 2;

Fig. 4 is a central vertical sectional view of the main part of the machine;

Fig. 4a is a sectional view on the line 4a—4a of Fig. 4;

Fig. 5 is a sectional view on the line 5—5 of Fig. 4;

Fig. 6 is an end view of the discharge end of the machine;

Fig. 7 is a perspective view of the end of a printing plate notched in accordance with this invention and constituting the product of this machine, and

Fig. 8 is a plan of a view plate looking in the direction of the arrow 8 in Fig. 6.

As stated, this machine performs no function except to provide a permanent register mark on a printing plate, particularly a plate of a semi-cylindrical shape on which a preliminary registering mark has been made. The preliminary mark is usually only a scratch 96 on the plate and a cross hair 97, or a series of them, on the stationary frame of the machine. The permanent mark is a notch 102 cut in each of the curved ends.

The machine is shown as carried by a main frame 1. Two brackets 2 and 3 are bolted to this frame permanently and serve as parts of the frame. They are located at opposite ends and to these two brackets are bolted horizontal brackets 4 and 5 carrying a plurality of rollers 6 mounted on studs 7 carried directly by the last named brackets. These rollers serve for supporting horizontally the opposite straight edges of a semi-cylindrical stereotype plate which has been provided with register marks. This bracket 2 and its several parts at the left of the machine constitute the receiving platform. In the same way the bracket 3 in its assembled form at the right of the machine constitutes the delivery platform.

Centrally located near the delivery platform near the top is a carriage 8 which contains suitable bearings for rotatably mounting the trunnions 8a of the plate saddle 9 which, of course, is curved to the shape of the stereotype plate.

It will be understood that the carriage 8 moves only in a longitudinal manner parallel to the axis of the plate saddle 9 and that the saddle, besides its movement with the carriage, can move only in an arcuate direction about its own axis. These two motions are used to bring into registration the two marks 96 and 97. Then the plate is held in that position while the notches 102 are made. These notches will be in the same position with reference to the register marks on all plates.

Slidably mounted on the plate saddle are clamps 10 and 11 at opposite ends which provide means for locking the concave printing plates 12 rigidly to the saddle. The clamps 10 and 11 are bolted respectively to two clamp arms 13, each of which mounts a nut 14 threadedly engaged on a right and left hand screw 15. This screw is mounted in two brackets 16 that are bolted to and become part of the saddle 9. This screw is held from longitudinal motion by a beveled gear 17 engaging one of the brackets 16 and a thrust collar 18 engaging the other and both fixed on the shaft.

Meshing with the bevel gear 17 is a bevel gear 19 fastened to the upper end of a vertical shaft 20. The shaft 20 carries a worm 21, a bushing 22 and a bottom bevel gear 23 for driving it. The shaft 26 is mounted in the bracket 16 and is held in position by the gears 19 and 23 and the bushing 22.

Meshing with the bevel gear 23 is a bevel gear 24 securely mounted on a shaft 25 that is mounted in, and carried by, the bracket 16. The shaft 25 is held from endwise motion by a washer 26 and thrust bushing 27. The shaft 25 extends through an opening in the frame 1 to a convenient position and supports at its outside end a hand wheel 28 by which it is manipulated to turn the shaft 15 and thereby move the clamps 10 and 11 always in opposite directions.

The worm 21 meshes with worm wheels 29 and 30 securely fastened to shafts 31 and 32 which are also mounted in the brackets 16. Attached to the outer ends of the shafts 31 and 32 are levers 33 and 34 respectively.

The plate saddle 9 contains vertical slots 35 and 36 in which are supported shafts 37 and 38 which carry a pair of brackets 39 and 40. These brackets 39 and 40 carry a plurality of rollers 41 supported on both sides by studs 42 on the brackets. This complete assembly will be referred to as a plate lifter. The plates will rest on this saddle while being notched and afterward will be lifted by the turning of the shaft 20 in such a direction as to raise the levers 33 and 34. These levers 33 and 34 eventually engage the shafts 37 and 38. Thus, when the plate clamps are opening, the shafts 37 and 38 are rising and operating the plate lifter to a position where the rollers 41 will be in alignment with the rollers 6 on the loading and receiving platforms.

It will be seen that the saddle 9 in combination with the clamping arrangement and plate lifter constitutes a unit in itself. Oscillation of the saddle does not affect any of the individual parts.

Operation of the hand wheel 28, through the combination of the gears and shafts described, will tend to open or close clamps 10 and 11 depending on the direction of the hand wheel ro-

tation. The worm 21 and worm wheels 29 and 30 are so designed that when the clamps 10 and 11 are closing the shafts 31 and 32 move the levers 33 and 34 away from the support shafts 37 and 38. When the clamps are opening the levers 33 and 34 are carried around against the support shafts 37 and 38 and raise the plate lifter upwards to a position where its rollers 41 will be in alignment with rollers 6 on the loading or receiving platforms. The plate rests on the rolls 41. Then a plate on the loading platform can be moved on the saddle in a straight line and one on the saddle can be removed.

Angular motion of the plate saddle 9 is accomplished by a hand wheel 43 placed to the left 15 of the hand wheel 28. The hand wheel 43 is attached to the other end of a screw 44 that is mounted in the frame 1 and in conjunction with a bracket 45 prevents the screw 44 from moving axially. A poppet 46 is threadedly mounted on the screw 44 and is rotatably mounted on one side in an extension 9a of the saddle 9 provided for this purpose and similarly mounted on the opposite side is a bracket 47 which in turn is secured to the hub of the plate saddle 9. Rotation of the hand wheel 43 will move the poppet 46 along the screw 44 and carry with it the plate saddle 9 and the lever 47 in an angular, or oscillatory, motion around the axis of the plate saddle 9.

Longitudinal motion of the carriage 8 is produced by rotation of a hand wheel 48 secured on the outer end of a shaft 49 mounted to the right of the hand wheel 28 on the front of the frame 1. On the opposite end of the shaft 49 is mounted a bevel gear 50 that meshes with a bevel gear 51 secured on a shaft 52. The shaft 52 is mounted in the frame 1 parallel to the plate saddle 9 and is held from moving longitudinally by the bevel gear 51 and a thrust collar 53 secured by lock nuts 54. The shaft 52 is threadably mounted in the carriage 8 and will move the carriage 8 when the shaft is revolved through motion of the hand wheel 48. This carriage 8 can move longitudinally of the machine in this way, taking the saddle and plate with it.

A plate to be prepared is placed upon the rolls 6 of the loading platform 2 and, with the plate lifter support shafts 37 and 38 at their high point, the plate is pushed along by hand until it strikes a pivoted stop 55. The plate stop 55 is pivoted in a bracket 56 by a pin 57 and is held in a raised position by a plunger 58 and spring 59. The bracket 56 is adjustable and is held by a thumb screw 60 to a bracket 61 that is bolted to the saddle 9.

The hand wheel 28 is then operated to close the clamps 10 and 11 and also cause the plate lifter rolls 41 to move away from the plate. By adjusting the hand wheels 43 and 48, it is now possible to make register marks 96 on the plate coincide with register marks 97 on or attached to the frame 1. When accurate alignment of marks is obtained, the plate is marked or notched on its curved edges by a suitable tool. In this case it is shown as a taper shank type broach 62 and 63 secured respectively in sleeves 64 and 65 slidably mounted in guides 66 and 67 that are bolted to the frame 1. The guides 66 and 67 are adjustable to regulate the position of the mark or notch. Screws 68 and 69 mounted in the frame 1, and held from axial movement by the collars 70 and 71 and shoulders on the screws, are threadedly mounted in guides 66 and 67 and adjust the position of the notch in the plate.

The guides 60 and 61 are so designed that they become guides for chips or dust and carry them to chip pans 94 and 95.

When the plate is ready to be notched, a switch (not shown), is operated and a driving motor 66, fastened to a shaft 67, rotates a worm 68 of the speed reducing mechanism. The motor 66 and speed reducing mechanism are located in the base of the frame 1. The shaft 67 is mounted by means of bushings 69 in a housing 70. The worm 68 meshes with a worm wheel 71 that is secured to a shaft 72. The worm wheel 71 is mounted in a housing 70 by bushings 73. The shaft 72 extends through both sides of the gear housing 70 and is supported by a bush 74 where it extends through the frame 1. Fastened to the right hand end of the shaft is a hub 75 supporting a cam 76 that operates a limit switch 77.

The shaft 72 also carries eccentrics 78 and 79 that operate crank rods 80 and 81 which are pivoted to the sleeves 58 and 59 by pins 82 and 83. The shaft 72 makes one complete revolution, carrying the broaches 56 and 57 up to notch the plate and returning them out of the way. The cam 76 revolves and when a rise 84 contained therein operates the limit switch 77 it will shut off the motor 66.

The plate is then ready for removal. The hand wheel 28 opens the clamps 10 and 11 and causes the plate lifter rolls 41 to push the plate 12 above the stop 55 which is depressed by hand, allowing the plate 12 to be pushed onto the rollers 6 of the delivering platform.

To insure accurate registering of the plates a framework 91, containing a view plate 92 with four openings communicating by means of mirrors 93 to the register marks on the plate is fastened to the frame 1. Suitable cross bars are mounted to coincide with the register marks placed preferably at the four corners of the plate.

It is now apparent that a number of like plates placed upon the machine and accurately registered and marked by means of the view plate and broaches may be placed upon a mounting containing pins or projections to suit the notches, and that corresponding parts on these plates will fall on identical spots. In other words, the plates can be placed on a finishing machine identically marked and all plates will be finished exactly alike. Any plates that are greatly out of register cannot be properly notched and will have to be thrown out.

Having thus described my invention and the advantages thereof, I do not wish to be limited to the details herein disclosed, otherwise than as set forth in the claims, but what I claim is:

1. In a plate registering machine, the combination of a receiving roller platform, a delivery roller platform in alignment therewith, a plate carrying saddle between the two platforms, means for adjusting said saddle longitudinally, and means for moving said saddle about its axis laterally to register a plate carried by the saddle.

2. In a plate registering machine, the combination of a plate carrying saddle, a carriage having bearings, trunnions, on opposite ends of the saddle resting in said bearings whereby the saddle will move longitudinally with the carriage, means for adjusting said carriage, and means for moving said saddle about its axis laterally to register a plate carried by the saddle.

3. In a plate registering machine, the combination of a plate carrying saddle, means for clamping a plate on the saddle, means for moving the saddle on its axis laterally to bring the plate

thereon into a definite registered position, and means for lifting a portion of the saddle to enable the plate to be removed from the machine.

4. In a plate registering machine, the combination of a receiving platform, a delivery platform in alignment therewith, a plate carrying saddle between the two platforms, means for adjusting said saddle longitudinally, means for moving said saddle about its axis laterally to register a plate carried by the saddle, and means for accurately forming a notch in a registered plate to enable all plates operated on by this machine to be notched exactly in the same place.

5. In a plate registering machine, the combination of a plate carrying saddle, means for swinging said saddle on its longitudinal axis to bring it into the desired position, plate clamps carried at opposite ends of the saddle, means for manipulating said plate clamps simultaneously toward each other to clamp a plate on a saddle, and means for accurately broaching a notch in each curved end of a plate on the saddle when the plate is in registered position.

6. In a plate registering machine, the combination of a saddle having two trunnions at opposite ends in alignment and bearings for said trunnions to mount the saddle in a swinging position, a horizontal shaft, a vertical shaft geared thereto, means operated by the vertical shaft for simultaneously lifting the saddle and unclamping the plate thereon for the purpose of bringing the saddle into a position for the plate to be discharged.

7. In a plate registering machine, the combination of a horizontal shaft, a vertical shaft, means for rotating the vertical shaft from the horizontal shaft, a worm on the vertical shaft, two worm wheels operated by said worm, each having a lever, a pair of supporting shafts which the levers are adapted to engage and lift when the vertical shaft has been turned far enough, a plate saddle, and plate supporting rolls movable with said support shafts and adapted to support the plate, whereby the plate supporting rolls will be lifted by the operation of said levers.

8. In a plate registering machine, the combination of a horizontal shaft, a vertical shaft, means for rotating the vertical shaft from the horizontal shaft, a worm on the vertical shaft, two worm wheels operated by said worm, each having a lever, a pair of supporting shafts which the levers are adapted to engage and lift when the vertical shaft has been turned far enough, a plate saddle, plate supporting rolls movable with the said support shafts and adapted to support the plate, whereby the supporting rolls will be lifted by the operation of said levers, means for clamping the plate to the saddle, a stop, and manually operated means for operating the first named horizontal shaft, whereby the stop will prevent further motion of the plate along the saddle and whereby the levers at the same time stop in a position to lift the supporting rolls and will lift them when the first named shaft is rotated further.

9. In a plate registering machine, the combination of a horizontal shaft, a vertical shaft, means for rotating the vertical shaft from the horizontal shaft, a worm on the vertical shaft, two worm wheels operated by said worm, each having a lever, a pair of supporting shafts which the levers are adapted to engage and lift when the vertical shaft has been turned far enough, a plate saddle, plate supporting rolls movable with the said support shafts and adapted to support

the plate, whereby the plate supporting rolls will be lifted by an operation of said levers, a pivoted stop at one end of the machine for stopping the motion of the plate along the saddle, means for clamping the plate to the saddle, and manually operated means for operating the first named horizontal shaft, the stop being movable down under the plate to allow the plate to be discharged over the stop, and a delivery platform for receiving the plate.

10. In a plate registering machine, the combination of a receiving roller platform, a delivery roller platform in alignment therewith, a plate carrying saddle between the two platforms, means for adjusting said saddle longitudinally, means for moving said saddle about its axis laterally to register a plate carried by the saddle, vertical guides on the machine, sleeves moving in said guides, broaches carried by said sleeves, 15 crank rods for operating said sleeves, a main shaft, cams on said shaft for operating the crank rods, a motor for rotating the shaft, an automatic means for stopping the motor when it has completed a revolution and moved the broaches 20 up on their cutting stroke and withdrawn them.

11. In a stereotype plate registering machine, the combination of a plate saddle arranged and adapted to support a curved stereotype plate thereon in relatively fixed position and having 25 oblong vertical openings therethrough, support shafts in said openings which support plate supporting rolls, a pair of parallel shafts having levers thereon, which are in a position to engage the support shafts and lift the plate supporting 30 rolls or to be retracted from them and let the plate supporting rolls down.

12. In a plate registering machine, the combination of a saddle and rolls thereon to support the plate, a pivoted spring-pressed stop at 40 the end of the saddle for limiting the movement of the plate in loading it, means for lifting the supporting rolls and the plate thereon, whereby, one depressing the stop by hand, the plate can be pushed off the saddle by hand.

13. In a plate registering machine, the combination of a receiving platform, a delivery platform in alignment therewith, a plate carrying saddle between the two platforms, means for adjusting said saddle longitudinally, means for 45 swinging said saddle about its axis laterally to

register a plate carried by the saddle, vertical guides on the machine inside the saddle, sleeves moving in said guides, broaches carried by said sleeves, crank rods for operating said sleeves to move the broaches outwardly, a main shaft, cams on said shaft for operating the crank rods, and means for rotating the shaft.

14. In a plate registering machine, the combination of a horizontal shaft, a vertical shaft, means for rotating the vertical shaft from the 10 horizontal shaft, a worm on the vertical shaft, two worm wheels operated by said worm, each having a lever, a pair of supporting shafts which the levers are adapted to engage and lift when the vertical shaft has been turned far enough, 15 means movable with the said support shafts to support the plate, means for clamping the plate to the saddle, a stop, and manually operated means for operating the first named horizontal shaft, whereby the stop will prevent further motion of the plate along the saddle and whereby the levers at the same time stop in a position to lift the supporting rolls and will lift them when the first named shaft is rotated further.

15. In a plate registering machine, the combination of a horizontal shaft, a vertical shaft, means for rotating the vertical shaft from the horizontal shaft, a worm on the vertical shaft, two worm wheels operated by said worm, each having a lever, a pair of supporting shafts which 20 the levers are adapted to engage and lift when the vertical shaft has been turned far enough, a plate saddle, means movable with the said support shafts to support a plate, whereby the plate supporting rolls will be lifted by the operation of 25 said levers, means for clamping the plate to the saddle, and manually operated means for operating the first named horizontal shaft, and a delivery platform for receiving the plate.

16. In a plate registering machine, the combination of a worm, two worm wheels operated by 40 said worm, each having a lever, a pair of supporting shafts which the levers are adapted to engage and lift when the vertical shaft has been turned far enough, a plate saddle, and plate supporting rolls movable with the said support shafts and adapted to support the plate, whereby the plate supporting rolls will be lifted by the operation of 45 said levers.
